CLOTHESLINE REEL

Walter J. Cutshall, Columbus, Ohio

Application October 29, 1938, Serial No 237,734

1 Claim. (Cl. 242—100)

The present invention relates to new and useful improvements in clothesline reels and has for one of its important objects to provide, in a manner as hereinafter set forth, a device of this character embodying novel means for clamping or securing the line after said line has been put up.

Another very important object of the invention is to provide a clothesline reel of the character described which may be expeditiously removed from its support when desired.

Other objects of the invention are to provide a clothesline reel of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figures 1 is a view in side elevation of a clothesline reel constructed in accordance with the present invention.

Figure 2 is a top plan view thereof.

Figure 3 is a view in vertical longitudinal section through the invention, showing a clothesline connected thereto.

Figure 4 is a detail view in front elevation of the bracket.

Figure 5 is a detail view in vertical section, taken substantially on the line 5—5 of Fig. 2.

Figure 6 is a detail view in vertical longitudinal section, taken substantially on the line 6—6 of Fig. 2.

Referring now to the drawings in detail, it will be seen that the embodiment of the invention which has been illustrated comprises a bracket which is designated generally by the reference numeral 1. The bracket 1 includes a plate 2 of suitable metal which is permanently secured through the medium of screws 3 on a post or other vertical support 4. Projecting from the upper and lower portions of the plate 2 are vertically aligned integral ears 5, said ears being apertured for the reception of a pin 6. The pin 6 is provided with a ball head 7 on its upper end to facilitate the removal of said pin.

The reference numeral 8 designates generally a substantially U-shaped frame which is also of any suitable metal. The legs 9 of the frame 8 terminate in bearings 10. Projecting from the

bight portion 11 of the frame 8 is an integral arm 12 which terminates, at its free end, in a vertically elongated eye 13 which is journalled on the pin 2 between the ears 5 in a manner to mount the frame 8 on the bracket 1 for swinging movement in a horizontal plane. As best seen in Fig. 1 of the drawings, the arm 12 is formed to provide a handle 14.

Rotatably mounted in the frame 8 is a reel which is designated generally by the reference numeral 15. The reel 15 includes a tubular hub 16 having keyhole slots 17 therein for receiving the knotted end 18 of a clothesline 19. The reel 15 further includes apertured heads 20 on the ends of the hub 16. The reel 15 is rotatably mounted in the substantially U-shaped frame 8 through the medium of trunnions 21 which are journalled in the bearings 10. An operating crank 22 is provided on one of the trunnions 21. The reference numeral 23 (see Fig. 5) designates 20 a friction brake for the reel 15 in the form of a set screw which is threadedly mounted in one of the bearings 10 for engagement with the corresponding trunnion 21. A lock nut 24 is provided on the brake 23 for securing same in adjusted position.

Projecting laterally from the arm 12 are integral stationary jaws 25. Pivotedly mounted on the bight portion 11 of the frame 8 are cam levers 26 which are adapted to coact with the 30 jaws 25 for releasably clamping the clothesline 19. This is shown to advantage in Fig. 6 of the drawings. The bight portion 11 of the frame 8 has formed therein recesses 27 in which the cam levers 26 are journalled on pins 28.

It is thought that the manner in which the device functions will be readily apparent from a consideration of the foregoing. The clothesline 19 is slidably engaged in a hook 29 which is mounted on the support 4 above the bracket 1. One end of the clothesline 19 is secured to the reel 15 by knotting said one end and inserting it in one of the keyhole slots 17. Of course, the other end of the line has been previously connected to a support. Then, by rotating the reel 15 through the medium of the crank 22 in a direction to wind the line thereon, said line is tightened. The line may then be engaged with one of the jaws 25 and secured by the corresponding cam lever 26. Thus, the line is prevented from unwinding from the reel 15. If the line has been previously wound on the reel 15 when the clothesline is put up, the free end of the line is carried to the other support and secured thereto. When this is done the line, of 55

course, is unwound from the reel 15. Through the medium of the brake 23 the reel 15 is prevented from rotating too fast as the line is drawn therefrom. The frame 8 with the reel 15 thereon 5 may be expeditiously taken down when desired by simply removing the pin 6. If desired, the end portion of the clothesline which is free of the reel 15 may be brought back, passed over the hook 29 and secured between the jaw 25 and 10 the corresponding cam lever 26 which are not in use.

It is believed that the many advantages of a clothesline reel constructed in accordance with the present invention will be readily understood 15 and although a preferred embodiment of the device is as illustrated and described, it is to be understood that changes in the details of con-

struction and in the combination and arrangement of parts may be resorted to which will fall within the scope of the invention as claimed.

What is claimed is:

A clothesline reel of the character described 5 comprising a substantially U-shaped frame, a supporting arm projecting from the bight portion of said frame, said bight portion of said frame having recesses therein adjacent the opposite sides of said arm, a reel journaled in the 10 frame, stationary jaws projecting laterally from the opposite sides of the arm in opposed relation to the recesses, and cam levers journaled in the recesses and cooperable with the stationary jaws 15 for securing a clothesline.

WALTER J. CUTSHALL.
